US00D624917S

(12) **United States Design Patent**
Andre et al.

(10) **Patent No.:** US D624,917 S
(45) **Date of Patent:** ** Oct. 5, 2010

(54) **MOUSE**

(75) Inventors: **Bartley K. Andre**, Menlo Park, CA (US); **Daniel J. Coster**, San Francisco, CA (US); **Daniele De Iuliis**, San Francisco, CA (US); **Evans Hankey**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Douglas B. Satzger**, Menlo Park, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/317,505**

(22) Filed: **Apr. 30, 2008**

(51) LOC (9) Cl. **14-02**

(52) U.S. Cl. **D14/408**

(58) Field of Classification Search ..... D14/402-410, D14/417; 345/163-167; 273/148 B; 358/471, 358/473

See application file for complete search history.

(57) **CLAIM**

The ornamental design for a mouse, as shown and described.

DESCRIPTION

FIG. 1 is a top, side perspective view of a mouse showing our new design;

FIG. 2 is bottom, side perspective view thereof;

FIG. 3 is a top view thereof;

FIG. 4 is a side view thereof, the opposite side view being identical thereto;

FIG. 5 is a bottom view thereof; and,

FIG. 6 is an end view thereof, the opposite end view being a mirror image thereof.

The broken lines are environmental and form no part of the claimed design.
